UNITED STATES PATENT OFFICE.

LEVI BATTEY, OF GLOVERSVILLE, NEW YORK.

MACHINE FOR MAKING EXCELSIOR.

SPECIFICATION forming part of Letters Patent No. 762,117, dated June 7, 1904.

Application filed May 2, 1903. Serial No. 155,293. (No model.)

To all whom it may concern:

Be it known that I, LEVI BATTEY, a citizen of the United States, residing at Gloversville, county of Fulton, and State of New York, have invented a certain new and useful Improvement in Machines for Making Excelsior, of which the following is a specification.

My invention relates to a new and useful improvement in machines for making excelsior, and relates to that class of machines having a reciprocating frame or slide carrying spurs or cutting-knives for dividing the wood into equal strips and also a blade or plane to shave the upper surface of the strips to form excelsior; and the object of my improvement is to provide a continually-lubricating bearing for the sliding parts; second, to provide a rolling series of knives in the place of spurs or stationary knives and also to provide means for adjusting the same, and, third, to provide a cleaning device or comb for keeping the rolling knives from all shavings and prevent the clogging of the same.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a plan view of my improved mechanism; Fig. 2, a longitudinal section through the same; Fig. 3, a cross - section through the device; Fig. 4, an enlarged detail longitudinal section of the means for adjusting the rolling knives, and Fig. 5 an enlarged 40 cross-section through one side of the slide and its bearing.

A represents the fixed or stationary frame of the machine, to which is secured the guides B, which guides have a longitudinal opening B' formed through the same, closed at both ends, and small lateral openings or holes B² arranged at intervals along the guide and extending from the interior to the exterior thereof.

C is the sliding frame, which has adjustably secured at each side of it the slide-bearings D, which slide upon the guides B. The opening B' in the guide B is adapted to be filled with a lubricant which will keep the slide continually lubricated by oozing through the 55 holes or openings B², formed in the guide.

E represents a series of circular knives arranged side by side upon a mandrel or shaft E', which shaft is journaled at each end in the arms F, which arms are pivoted at one end to the sliding frame C and have swiveled through the other end the threaded bolts G, which are threaded into the slide C for the purpose of adjusting the knives up or down. The bolts have flanges against which the arms 65 bear. This series of rolling knives forming the cutter extends through an opening C', formed through the slide C, and is adapted to come in contact with the board H, from which the excelsior is made, and as the slide C reciprocates the cutter will cut into the board 70 a predetermined distance and cut the same into strips of equal width.

I is a comb or cleaning device composed of a number of teeth which extend in between 75 the knives of the cutter and keep the same clean and prevent any clogging of the knives.

J is a shaving blade or plane which is adjustably secured to the slide C and follows the cutter and passes through the slide C and 80 comes in contact with the board H, so as to shave off the strips formed by the knives E, thus forming excelsior. The cutting edge of this blade J is oblique, as shown in Fig. 1, and cuts with a shearing action which greatly 85 facilitates the forming of the excelsior.

Of course I do not wish to be limited to the exact construction here shown, as slight modifications could be made without departing from the spirit of my invention.

Having thus fully described my invention, what I claim as new and useful is—

In an excelsior - cutting machine, a frame having suitable guides, a sliding frame having a transverse aperture, bearings adjustable on the sliding frame, screws carried by the sliding frame seated against the edges of the bearings for retaining said bearings in

place, arms pivoted on the sliding frame, knives rotatably mounted on the arms, a flanged bolt in the end of each arm for adjusting the height of the arms, and a shaving-knife suitably mounted on the sliding frame, substantially as described.

In testimony whereof I have hereunto af-

fixed my signature in the presence of two subscribing witnesses.

LEVI BATTEY.
